UNITED STATES PATENT OFFICE.

GEORGE C. GARDNER, OF CHICAGO, ILLINOIS.

DESIGN FOR A CASING FOR DOOR-HANGER FRAMES.

SPECIFICATION forming part of Design No. 27,299, dated July 6, 1897.

Application filed May 27, 1897. Serial No. 638,310. Term of patent 7 years.

To all whom it may concern:

Be it known that I, GEORGE C. GARDNER, a citizen of the United States of America, residing at Chicago, in the county of Cook and 5 State of Illinois, have invented and produced a new and original Design for an Outer Casing for Door-Hanger Frames, of which the following is a specification.

My invention relates to a certain new and 10 useful configuration for an outer casing for door-hangers.

The invention is illustrated in the drawings by means of three figures, of which—

Figure 1 is a face view of said outer casing. 15 Fig. 2 is a section of the same in line 2 2, looking in the direction of the arrow 2. Fig. 3 is a section of the same in line 3 3, looking in the direction of the arrow 3.

The outer casing here shown is of substan-

tially uniform thickness and has at the top 20 an outwardly-convex circular corrugation A, almost a complete circle, but having the lower portion omitted, and two downwardly-extending corrugations A' A² substantially continuous with the circular corrugation A. 25

The essential feature of my design I consider to be the circular corrugation A, having the downwardly-extending corrugations A' A² substantially continuous therewith.

I claim as new and desire to secure by Letters Patent—

The design for an outer casing for door-hangers, herein shown and described.

GEORGE C. GARDNER.
